UNITED STATES PATENT OFFICE.

CARL GUSTAV MORGNER, OF CHICAGO, ILLINOIS.

WINDOW SCREEN.

Application filed October 12, 1922. Serial No. 594,067.

To all whom it may concern:

Be it known that I, CARL G. MORGNER, a citizen of the United States, residing at Chicago, in the county of Cook and State of Illinois, have invented certain new and useful Improvements in Window Screens; and I do declare the following to be a full, clear, and exact description of the invention, such as will enable others skilled in the art to 10 which it appertains to make and use the same.

My invention relates to improvements in vertically slidable closures, such as window screens and has reference more particularly 15 to screens designed primarily for use in connection with the windows of passenger cars.

The principal object of the invention is to greatly simplify and improve upon the constructions shown by my U. S. Patents 20 Nos. 1047828 of Dec. 12, 1912 and 1071565 of August 26, 1913.

In carrying out the above end, a further object is to provide a novel arrangement of pivoted arms carried by the screen and 25 normally occupying positions against the latter when it is lowered, said arms however being movable downwardly to vertical positions to engage the screen guides and hold the screen in raised position when its 30 use is not necessary.

A further object is to provide unique means for holding the screen in lowered position, said means being controllable by the arms above referred to.

Yet another object is to make novel provision for detachably holding the screen in engagement with its guides.

With the foregoing and minor objects in view, the invention resides in the novel subject matter hereinafter described and claimed, the description being supplemented by the accompanying drawings.

Figure 1 is a side elevation of a screen constructed in accordance with my invention, showing also the vertical screen guides and the window frame which carries these guides.

Figure 2 is a vertical transverse section as indicated by line 2-2 of Fig. 1 and the line 1-1 on this view indicates the plane on which the window frame is cut in Fig. 1.

Figure 3 is an enlarged vertical section partly in elevation, showing the screen raised and held in raised position.

Figure 4 is a perspective view of a portion of one of the screen guides.

Figure 5 is a perspective view of the free end of one of the pivoted arms which engages the portion of the guide shown in Fig. 4 to hold the screen raised. 60

Figure 6 is an enlarged vertical section through the lower end of a portion of the screen and associated parts, showing the manner in which said screen is held in lowered position. 65

Figure 7 is a duplicate of Fig. 6 with the exception that it illustrates the screen-holding means released so that the screen may be raised.

Figure 8 is a view similar to Figs. 6 and 7 but illustrating the relation of parts when the screen stands in its raised position. 70

Figure 9 is an edge view of the lower portion of the screen in the condition shown in Fig. 6 or Fig. 7. 75

Figure 10 is an edge elevation of the lower portion of the screen with the parts in the position shown in Fig. 8.

Figure 11 is a horizontal section on line 11-11 of Fig. 8, looking upwardly as indicated by the arrows. 80

Figure 12 is a detail horizontal section of the screen frame only, as indicated by line 12-12 of Fig. 7. 85

Figure 13 is a detail vertical section as indicated by line 13-13 of Fig. 7.

Figure 14 is a detail vertical section on line 14-14 of Fig. 7.

Figure 15 is a perspective view of the pivoted end of one of the swinging arms 90 and the spring pressed plunger to which this arm is pivoted.

Figure 16 is a detail horizontal section on line 16-16 of Fig. 3.

Figure 17 is a horizontal section with 95 parts in elevation as indicated by line 17-17 of Fig. 3.

Figure 18 is a duplicate of Fig. 17 with the exception that it illustrates a spring pressed latch held in retracted position so that the vertical filler bar between the screen and one of the vertical guides thereof may be turned to permit removal of said screen. 100

Figure 19 is a detail elevation, partly in vertical section, showing a slightly different form of construction from the preceding views. 105

Figure 20 is a horizontal sectional view on line 20-20 of Fig. 19.

In the drawings above briefly described, 110 the window frame 1 and the sash or sashes are considered as being about the same as

those disclosed in the previous patents above referred to, and hence are not described. The numeral 1 however is applied to the frame for sake of reference. Secured to the opposite sides of this frame 1, are a pair of vertical screen guiding strips 2 commonly known as parting strips, each of these strips being preferably stamped or rolled from a single length of sheet metal as shown for instance in Figs. 16, 17 and 18, the formation of each of the strips being such that its inner side is provided with a longitudinal groove or channel 3 which is preferably of substantially semi-circular form in transverse section. Slidably engaged with one of the strips 2 and having a rounded edge received in its groove 3, is one vertical side 4 of a screen frame 5, the other vertical side 6 of this frame having a rounded edge 7 which is spaced from the groove 3 of the other strip 2, the space being occupied by a filler bar 8 which is preferably of concavo-convex form in transverse section, so that its convex side 9 is receivable within the groove 3 of the last named strip 2, while the concave side 10 of the bar receives the rounded edge 7 of the frame side 6. A spring projected latch bolt 11, shown most clearly in Figs. 3, 17 and 18 is mounted in the upper side bar of the frame 5 and is normally forced by its spring into an opening 12 in the inner side of the bar 8, whereby to hold this bar against rotation and to connect it rigidly with the frame 5. When the latch bolt is in this position, a shoulder 13 with which it is provided, thrusts outwardly against the bar 8 and thereby yieldably holds the latter against its co-acting strip 2, so as to exert a braking action which prevents accidental dropping of the screen when raising or lowering the same and manipulating the swinging arms yet to be described. When the bolt 11 is retracted as shown for instance in Fig. 18, the filler bar 8 may be turned about its longitudinal axis, by means of a suitable finger piece 14 which is shown on said bar in Fig. 1. Thus, the concave side 10 of this bar and its convex side 9 are disengaged from the edge 7 and the groove 3 respectively, sufficiently to permit the entire bar to be removed. This allows lateral play of the screen and consequently it may readily be removed from the window frame.

As it is customary to remove the screens at certain seasons and again apply them at other times, but is inadvisable to have the latch 11 of such nature that the passengers could release the same, I prefer that this latch shall be totally confined within the upper bar of the screen frame 5, but in order that said latch may be released by means of a suitable instrument, I form a slot 15 in the frame bar giving access to a socket 16 in the latch. By inserting one end of a U-shaped

instrument such as that shown at 17 in Fig. 18, into the socket 16, the bolt 11 may easily be retracted, whereupon the other end of said instrument 17 may be passed into an opening 18 in the upper bar of the screen frame, thereby holding the latch released while the bar 8 is being turned. When turning the bar, it is also necessary to move the finger grips 32 toward each other and hold them by any suitable means such as a substantial duplicate of the device 17, whose ends may be engaged with said grips.

The numerals 20 designate a pair of vertically swinging arms connected with the lower corners of the screen frame 5, said arms normally lying against the screen frame when the latter is lowered. These arms are preferably of channel form in transverse section as shown for instance in Figs. 5, 10 and 15, so as to lie under and receive the lower rounded edge of the screen frame when the latter is lowered. See for instance Figs. 6 and 7. When the screen is raised however, the arms 20 swing downwardly as illustrated in Figs. 1 and 3 and then engage the strips 2 to support said screen in its elevated position. To provide for proper engagement of the arms 20 with the strips 2, I prefer to provide the construction detailed in Figs. 4-5. It will be seen from these figures that the free end of each arm 20 is provided with a finger 21 extending in the direction of its length and that the strips 2 are each provided with a recess 2' to receive the finger 21 of the adjacent arm. This arrangement is also illustrated clearly in Fig. 3. The recess 2' is cut entirely through the inner side wall of the guide strip 2 so that the finger 21 may hook over the lower edge wall 23 of said recess, whereby it cannot be disengaged until the screen 5 is moved slightly upward from its normal raised position. When this is done, the finger 21 strikes a cam 24 at the upper end of the recess 22 and hence is forced inwardly out of alignment with the end wall 23. Thus, when the screen frame 5 is lowered, the finger 21 will not again engage said end wall 23, but the screen may be lowered, it being of course understood that during the lowering operation, the arms 20 are again swung upwardly under the lower edge of the screen frame 5 so as to permit the latter to move entirely to its lowest position.

I prefer to associate some suitable means with the arms 20, for the purpose of holding the screen frame 5 in its lowered position. In the preferred form of my invention, I provide each of the arms 20 with a flat head 25 which passes through a slot 26 in the lower edge of the frame and is pivoted at 27 in a bifurcated plunger 28, the latter being located within a lower corner of the frame 5 and being projected normally out-

ward by a suitable spring 29. The head 25 is provided with a projecting nose 30 which, when the arm 20 is swung to its horizontal position as in Fig. 5, is received in a notch 31 in the inner side of the guide strip 2. It will thus be seen that the screen frame 5 cannot be raised until the arm 20 is pulled inwardly and the nose thus disengaged from the notch 31 as indicated in Fig. 7.

It is of course understood that the construction just described is associated with each of the arms 20 and in order that both of these arms may be simultaneously moved inwardly against the tension of the springs 29, I provide the free ends of said arms with finger grips 32 which are sufficiently close together when the arms 20 are horizontal to permit them to be moved toward each other by the thumb and forefinger of one hand. When these grips are thus moved to release the noses 30 from the notches 31, the arms 20 may be swung downwardly as in Fig. 8, after the frame 5 has been raised sufficiently to permit this movement. Then by grasping the finger grips 32, the frame may be raised to the maximum amount and the fingers 21 engaged with the recesses 22 so as to hold said frame raised. When the arms 20 stand in the last named position, the noses 30 preferably abut the stop surfaces or shoulders 33 within the corners of the frame as shown in Fig. 8 so that the entire weight of the screen is taken from the pivots 27. If desired, the heads 25 may each be provided with a stop nose 34 to engage the stop shoulder 35 on the plunger 28 when the arm is lowered (see Fig. 8). These stop noses 34 may well engage the stop surfaces or shoulders 33 when the arms 20 are horizontal as in Fig. 6. Thus, when the screen is lowered, possibly with quite a jar, there is no danger of injuring the pivot pins 27.

In the preferred form of construction, the vertical side bars 4 and 6 of the frame 5 are connected with the bottom bar by means of suitable corner blocks 36 extending into and riveted to the adjacent ends of these bars, and these corner blocks are preferably recessed to receive the movable parts associated with the pivoted ends of the arms 20 as shown in several of the views. These corner blocks may of course be solid or hollow, and of any desired configuration to obtain the desired results.

The screen wire 37 is preferably secured to the frame 5 in the manner shown, but as this detail of construction is very similar to the corresponding construction of my previous patents, it need not be described in detail.

In connection with the features of construction above described, I may use a wear strip 8^a interposed between the frame side 4 and the adjacent guide strip 2, as seen in

Figs. 19 and 20, said strip 8^a being detachably connected with the frame side 4 in any desired manner.

From the foregoing, taken in connection with the accompanying drawings, it will be seen that I have greatly simplified and cheapened the construction of the previously patented screens, without in any manner decreasing the efficiency thereof. Attention is directed to the fact that whereas the screen cannot be readily removed from its guides by an unauthorized person, the passengers can readily raise or lower said screen, as they may desire. Excellent results have been obtained from the details disclosed and they are therefore preferably followed, but within the scope of the invention as claimed, numerous minor changes may of course be made.

I claim:

1. The combination with a vertically movable closure and guides for the vertical edges thereof; of an arm pivoted to one lower corner of said closure and occupying a position against the closure when the latter is lowered, said arm being downwardly movable to a vertical position when the closure is raised and being then engageable with one of said guides to hold the closure in raised position.

2. The combination with a vertically movable closure and guides for the vertical edges thereof; of an arm pivoted to one lower corner of said closure, said arm being longitudinally channeled and receiving the lower edge of the closure when the latter is lowered and being movable downwardly to a vertical position when the closure is raised, said arm when lowered being engageable with one of said guides to hold the closure in raised position.

3. The combination with a vertically movable closure and guides for the vertical edges thereof; of means for holding the closure in lowered position, and an arm for releasing said holding means, said arm being pivoted to the lower end of the closure and being downwardly movable to a vertical position when the latter is raised, said arm being then engageable with one of said guides to hold the closure raised.

4. The combination with a vertically movable closure and guides for the vertical edges thereof; of an arm connected to one lower corner of the closure for vertical swinging and for movement toward and from one of said guides, said arm normally occupying a position against the closure and having a portion which then engages one of said guides to hold said closure lowered until the arm is shifted inwardly, said arm being downwardly movable to a vertical position when the closure is raised and being then engageable with said guide to hold said closure raised.

5. A structure as specified in claim 4; together with spring means for engaging said arm with said guide when the closure is lowered.
6. The combination with a vertically movable closure and guides for the vertical edges thereof, of a horizontally movable plunger carried by one lower corner of said closure, an arm pivoted to said plunger and normally occupying a position against the closure, a spring for then forcing said plunger outwardly to engage the pivoted end of said arm with one of said guides and hold the closure lowered, said arm being downwardly movable to a vertical position when the closure is raised and being then engageable with said guide to hold said closure raised.
7. The combination with a vertically movable closure and guides for the vertical edges thereof, of a spring-pressed plunger mounted in one lower corner of said closure for horizontal sliding, said closure having a slot in its lower edge giving access to said plunger, an arm normally lying horizontally at the lower edge of said closure, said arm having a flat head at its outer end passing through said slot and pivoted to said plunger, said head having a shoulder normally engaging one of said guides under the influence of the plunger spring to hold the closure lowered until said arm is pulled inwardly, said arm being downwardly movable to a vertical position when the closure is raised and being then engageable with said one guide to hold the closure raised.
8. The combination with a vertically movable closure and guides therefor; of means at the lower corners of said closure for engaging said guides and holding the closure in lowered position, a pair of pivoted and slidable arms extending inwardly toward each other along the lower edges of the closure for releasing said holding means when said arms are slid inwardly toward each other, the inner ends of said arms having finger grips for so sliding them; said arms being downwardly movable and engageable with said guides when the closure is raised.
9. The combination with a vertically movable closure and guides therefor; of an arm pivoted to said closure and movable downwardly to a vertical position when the closure is raised, said arm having a finger on one side extending lengthwise of said arm, one of said guides having a recess to receive said finger when the closure is raised.
10. The combination with a vertically movable closure and guides therefor; of an arm pivoted to said closure and movable downwardly to a vertical position when the closure is raised, said arm having a finger on one side extending lengthwise of said arm, one of said guides having a recess to receive said finger when the closure is raised, and a cam at the upper end of said recess to move said finger from the latter when the closure is raised slightly above its usual raised position.
11. A structure as specified in claim 1; said closure and arm having coactive surfaces for supporting the former from the latter independently of the arm pivot when the closure is raised.
12. The combination with a vertically movable closure having a rounded vertical edge and a vertically grooved guide strip spaced outwardly from said edge; of a filler bar interposed between said guide strip and said rounded edge, said bar having a concave side engaging said rounded edge and a convex side received in the groove of said guide strip, and releasable means for holding said filler bar against turning between said strip and edge until it is desired to remove the closure.
13. The combination with a vertically movable closure having a rounded vertical edge and a vertically grooved guide strip spaced outwardly from said edge; of a filler bar interposed between said guide strip and said rounded edge, said bar having a concave side engaging said rounded edge and a convex side received in the groove of said guide strip, and a spring pressed latch carried by the closure and engaging said filler bar to prevent turning thereof until the closure is to be removed.
- In testimony whereof I have hereunto affixed my signature.

CARL GUSTAV MORGNER.
